FOOTBALL GAME

Frank R. Graves, Rochester, N. Y.

Application July 3, 1947, Serial No. 758,858

3 Claims. (Cl. 273—94)

1

The present invention relates to a game and to apparatus for playing the same, and particularly to a game simulating the outdoor game of football, and to apparatus for playing such a game indoors.

One object of the invention is to provide a game which two or more persons can readily play with relatively inexpensive equipment and which will engender plays and situations closely resembling those encountered in a regulation game of football, thereby making the game enjoyable not only to regulation football fans but to any players.

Another object of the invention is to provide a game, simulating football, which can be played either as a game of skill or as a game of chance.

Still another object of the invention is to provide a game board for a football game, which is lined as to yardage like a football field, but which is laid out in such wise as to keep the playing space within easy reach of two players.

Other objects of the invention will be apparent hereinafter from the specification and from the recital of the appended claims.

In the drawings:

Fig. 1 is a plan view of a game board constructed according to a preferred embodiment of this invention;

Fig. 2 is a plan view of an auxiliary board adapted to be used with the main board to keep track of the number of plays and also for determining the moves of the players when the game is being played as a game of chance;

Fig. 3 is a fragmentary sectional view through the board of Fig. 1 showing one way in which the indicating hands of the playing field may be mounted.

The game may be played as a game of chance with a spinner or with dice, or as a game of skill, either with a standard deck of playing cards or with a deck specially made for the purpose.

A simulated football field is used for keeping track of play. This field is marked off in graduations designated as yards, and it is one hundred yards long like an ordinary football field. It differs from the standard football field, however, in that it is laid out in a circle. The graduations around one half of the circle are numbered from 1 to 50 and the graduations around the other half of the circle are numbered from 50 to 1. Thus, one half of the circular field corresponds to one half of the playing field of a standard football gridiron and the other half of the circular field corresponds to the other half of a standard football gridiron. With this arrangement, both goal lines and both end zones are at the same end of the field.

The circular layout of the playing board simplifies the playing of the game and keeps it within easy working compass.

The game follows generally the ordinary rules of outdoor football. When the ball is put into

2

play, the offensive player has to gain ten yards in four plays or he loses possession of the ball. If a player carries the ball across his opponent's goal line, he scores a touchdown which is 6 points.

If the defensive player is pushed back over his own goal line, a safety is scored for his opponent which is 2 points. The game is divided into quarters like regulation football, but 24 plays constitute a quarter when playing the game with either a spinner or dice, while when a deck of playing cards is used, the quarter ends when all of the cards in the deck have been played, as will be described further hereinafter.

Referring now to the drawings, B designates a board made of a suitable material, and preferably having the shape of a football, on part of which the playing field F is laid out. This field is circular in form. It is graduated by equi-spaced parallel straight lines 100, which define spaces 101 that are designated as "yards" for the purpose of play.

The field is divided in the center by a diametrical line 101. There are fifty-one of the spaces 101 on the field. One space (the bottom space 25 in Fig. 1) is designated as the "Goal lines." The other spaces denote yards. They are numbered around the left hand side of the field, reading clockwise, 1 to 50 and around the right hand side of the field 50 to 1, the numerals designating the 30 different yards being placed between the concentric circles 102 and 103. Thus, the half of the field at the left of the line 101 corresponds to one team's territory in a game of football and the 35 half at the right of line 101 corresponds to the opposing team's territory, the goal lines being at the ends of the respective territories.

A space designated "End zones" may be marked off beneath the space, "Goal lines," just to carry further the similarity to a regulation 40 football gridiron. If desired, the two halves of the field may be differently colored to distinguish them clearly.

Printed on the playing field are various notations such as "Penalty against defense," "Penalty against offense," etc., by which the present game 45 may be made to correspond in play as closely as possible to a regulation game of football as will be apparent hereinafter.

Secured in the board B is a grommet 106 (Fig. 50 3) on which are rotatably mounted two indicating hands or pointers 104 and 105. The upper indicator 105 denotes the position of the ball on the field, while the lower indicator 104 denotes the number of yards to be gained in a given series 55 of four plays. As stated, the ball is put in play on the twenty-six yard line. Thus, at the start of the game, the indicator 105 is placed opposite the numeral 26 at the left end side of the playing field and the indicator 104 is moved to register 60 with the numeral 36 at the same side of the playing field, since, when the ball is put into play,

the offensive player has ten yards to go in four downs.

Let us assume that the game is being played as a game of chance with a spinner. A dial, such as shown of 110 in Fig. 2 may be used. This dial may be mounted upon a board B', smaller than board B but also preferably shaped like a football. The dial is made to have any desired number of segments 111. The segments are numbered consecutively 1 to 10, 15, 20, and 25, around one half of the dial and 1 to 10, 15, 20, and 25 around the other half of the dial. Alternate segments are preferably made of contrasting color as, for instance, black and red. Thus, the segments shown marked with erect numerals may be black, while the segments shown marked with slanting numerals may be red. In the embodiment shown, the dial has twenty-six segments.

The spinner hand 112 is rotatably mounted above the dial in the conventional manner in such a way as can be easily spun by a flip of the finger. If the spinner hand 112 stops opposite a black segment, the player making the spin gains the number of yards indicated on that segment. If the hand stops opposite a red segment, the player loses the number of yards on that segment. Thus, if on the first spin the pointer 112 stops opposite the numeral 7 on a black segment, the player gains 7 yards and he moves the indicator 105 on the playing field F to the 33 yard line, indicating the new position of the ball. The indicator 104 is left where it is at 36. If, on the other hand, the pointer 112 stops at 10 on a red segment, the player loses 10 yards and he moves indicator 105 back, that is, counterclockwise, to register with numeral 16, indicating the new position of the ball. The indicator 104 is left at 36, however, and the offensive player now has twenty yards to gain in but three plays.

The offensive player now spins again. If he gains enough yards in four spins or less to move the ball, that is, the hand 105, beyond the 36 yard line, he has made a first down and he has four more plays in which to gain another 10 yards, just as in a game of football. If he fails to gain 10 yards, that is, fails to move hand 105 past the 36 yard line in four spins, he loses possession of the ball and his opponent takes possession of it at the point where hand 105 is, that is, at the point where possession of the ball was lost. The opponent then has the right to spin the pointer 112, and he has four plays to gain ten yards into the first player's territory. If, for instance, the first player succeeds in moving the ball, that is, the indicator arm 105, only to the 35 yard line in four spins, his opponent will take possession of the ball from that yard line, and will first move the hand 104 to the 25 yard line indicating the distance which he has to gain in four spins. If the second player gains this distance in four spins or less, he continues in possession of the ball and has another four spins. If he fails to make the distance, the first player again takes possession of the ball.

If the player who starts the game succeeds in advancing the ball to a point where the yardage to be gained is beyond his own fifty yard line, the pointer 104 is moved over to the right hand side of the field to the appropriate point in his opponent's territory. Likewise, if the first player is able to advance the ball beyond the 50 yard line at his own side of the playing field, the pointer 105 is moved to register with the proper numeral indicating yardage at the right hand

side of the field and play is now in the opponent's territory.

When either player has moved the ball across his opponent's goal line, he scores a touchdown, that is, six points. Then the ball is moved out to his opponent's two yard line and he has one play, spin, in which to make that distance. If he succeeds, he gets one point, which corresponds to the point after touchdown in a regular game. Regardless of the outcome of the attempt for point after touchdown, the possession of the ball is now shifted, and the other player takes possession of the ball on his own 26 yard line with four downs in which to make 10 yards, as in a regular game.

If the player is pushed over his own goal line, then a safety is scored, but he does not lose possession of the ball. The ball is put into play again at the 20 yard line just as in football.

Downs may be kept track of by a pointer 115 (Fig. 1) which is adapted to register with the numerals 1, 2, 3 and 4 inscribed on quarters of the circle or dial 116 which is mounted on or formed integral with the board B. The number of plays in each quarter are kept track of by a pointer 120 (Fig. 2) which may register with any one of the numerals 1 to 24 on the dial or circle 121, that is secured to or formed integral with the board B'. There are twenty-four plays in a quarter and, of course, four quarters in a game. Possession of the ball changes at the halves as in regular football. The quarters may be kept track of by the pointer 125 (Fig. 1) which registers with the numerals 1, 2, 3 and 4 on the quarters of the dial 126 that may be integral with or secured to the board B.

If, as a result of its movement, the pointer 105 registers at any time with any one of the numerals 4, 8, 14, 18, 24, 28, 34, 38, 44, or 48 at either side of the field, a further move is made in accordance with the legend in that particular yard space. Thus, for instance, if the pointer 105 registers with the 28 yard line as a result of a play, or spin, there is a 15 yard penalty against the defense, which means that the ball, that is, the pointer 105 is further moved to the 43 yard line or to the 13 yard line depending on which player has possession of the ball at the time and on which side of the field the ball is in play. As another instance, if the pointer 105 should register, as a result of a play or spin, with the 34 yard line at either side of the field, the offensive player would score three points if the ball is in his opponent's territory, as though he had kicked a field goal from the thirty-four yard line in a regulation game of football.

When the game is played with dice, the moves are just the same as described for the game played with a spinner. There are two pair of dice used, that is, a total of four dice. The two pairs of dice are differently colored, respectively, or distinguished from one another in some other suitable fashion. Thus, one pair may be red and another pair white.

The player who has possession of the ball rolls all four dice. One pair of dice, for instance, the red dice, indicates a loss of yardage, while the other pair of dice indicates a gain of yardage. The difference between the totals of the two pair of dice will give the yardage gained or lost. If the player in possession of the ball throws a one and a three on the red dice and a four and a six on the white dice, he scores a total gain of 6 yards and he moves the pointer 105 accordingly just as he would do if we were using the spinner.

Each player has four rolls in which to gain 10 yards. If he succeeds, he continues to roll until he has scored a touchdown or fails to gain 10 yards in four rolls. When he fails to gain the required distance, the other player takes the dice, and it is now his turn to try to gain ten yards in four downs or less. As when the game is played with a spinner, there are 24 plays to a quarter. Likewise, the legends on the board are followed when the hand 105 registers against a space which contains a legend.

The game may also be played with a deck of cards. This may be a standard deck of 52 playing cards such as used in a game of poker.

If standard cards are used, the black cards, namely spades and clubs, indicate gains in yardage whereas the red cards, hearts and diamonds indicate loss in yardage. The cards are valued as follows:

	Yards
King	25
Queen	20
Jack	15
Ten	10
Nine	9
Eight	8
Seven	7
Six	6
Five	5
Four	4
Three	3
Two	2
Ace	1

The deal may be determined by the toss of a coin or by cuttings the cards or in any other way. The winner deals and the other player becomes the player in possession of the ball. The game is started as before on the 26 yard line with the hand 105 registering against the numeral 26 at the offensive player's side of the field and the hand 104 registering against the numeral 36 at this same side of the field. Three cards are dealt to each player, one at a time. The balance of the deck of cards is placed face down in the center of the table. The player in possession of the ball plays first. He plays one card face up. Since he is in possession of the ball he tries to make a gain, so that, if he has black cards in his hand he plays ordinarily the highest black card of the three cards he has in his hand. His opponent tries to prevent him from gaining; so ordinarily he plays the highest of the red cards which he possesses, if he has a red card. Otherwise, the opponent will usually play the lowest black card that he has. If one player has played a black card and the other a red card, the values of the two cards are subtracted from one another. If the black card is the larger, a gain is scored by the player in possession of the ball. If the red card is the larger, a loss is scored.

Let us assume that the first player puts down the queen of spades and the second player the ten of diamonds. The first player would then gain 10 yards; and there would be a new first down. If the first player has no black cards, however, and has to play a red card, say the three of hearts, and his opponent lays down the ten of diamonds, then the first player loses 13 yards. If the second player has no red cards, only black cards, and the first player lays down a queen of clubs and the second player the nine of spades, the first player would score a total gain of 29 yards, which would bring him past the center of

the field to the 45 yard line at the right hand side of the field.

After playing a card, each player draws another card from the pack. Then the players play again. 5 Again the total of the cards laid face up is counted and the pointer 105 shifted accordingly to indicate yards gained or lost. When all of the cards in the deck have been played, that constitutes a quarter. Four quarters are played as in the standard game.

The ace may be used to count as a one yard gain or loss, depending upon whether it is a black or a red ace, or it may be used to count as a loss of ball. In some cases in order to avoid a heavy penalty, for instance, where the player in possession of the ball sees that his move would put him on the 38 yard line which entails a 15 yard penalty, he may use the ace to indicate loss of the ball and so avoid this penalty. This is optional. It is preferable to determine before the game is started whether the ace shall be used to denote loss of the ball or to count simply as a yard. When the game is played with the aces indicating losses of the ball, the player must call 10 the play, when he lays down an ace, either as a one yard play or as a loss of the ball.

Other than in the respects noted, the game as played with cards is exactly like the game as played with a spinner or with dice. The player in possession of the ball has four plays or downs in which to gain ten yards. If he gains ten yards in four plays or less, he has a new series of four plays or downs in which to gain another ten yards. If he fails to gain the ten yards in four downs his 15 opponent takes possession of the ball, and the opponent then has to gain ten yards against the first player in four downs. If a play carries pointer 105 to one of the spaces 107, which bears a legend, the ball, that is, pointer 105, is moved a further distance in a direction indicated by that legend. If the player carries the ball, that is, moves the pointer 105, across his opponent's goal line, he scores six points; then he moves the ball (pointer 105) to his opponent's two yard line, 20 and tries to gain that two yards in one play. If he does, he scores a single point for point after touchdown. Whether he gains the single point or not, possession of the ball changes and the opposing player now takes possession of the ball on 25 his own 26 yard line with ten yards to gain in four downs. The quarter ends when all the cards in the deck have been played.

The game is usually played by two players only. However, it may be played by any number of 30 players.

When it is played with a spinner or dice by more than two players, the players play as partners. In this case one player may spin pointer 112 for one play, and successive plays may be 35 spun by the different players, the right to spin going to the player next to the left of the player who has spun the pointer on the previous play.

A partnership game may also be played with the spinner by totaling the spins of all players.

40 Thus, if four persons are playing the game, one of the offensive players may spin first; then the defensive player to his left; then the offensive partner; and then the defensive partner. The total of black and red spins will then indicate 45 yards gained or lost by the offensive. Thus, if the first offensive player's spin stops with the pointer 112 at 9 in the black; the first defensive player's spin stops with the pointer 112 at 4 in the red; the second offensive player's spin stops 50 at 4 in the red; and the second defensive player's

spin stops at 2 in the black, the offensive will gain 3 yards.

When the game is played with dice by partners one player may roll the dice for one play and then the player to his left may roll the dice for the next play; or all players may roll on each play and the totals of the red and black dice thrown by them all may be added to determine the yardage gained or lost on the play.

When the game is played with cards by more than four persons, it is usual for all players to play one card on each play and to use two decks of standard playing cards, dealing three cards to each player to start the game. Partners try to help each other by playing black cards if on the offensive or red cards if on the defensive. The total of the black cards less the total of the red cards played on any round gives the yardage gained or lost.

If the game is played with three players, then it is played as "cutthroat," two of the players playing against the one having possession of the ball. This is true for any odd number of players, the other players playing against the one having possession of the ball.

During the game partners can suggest to each other what plays to make, or use signals, but they cannot show their cards. If cards are shown, the player is penalized 5 yards.

Obviously, instead of using a standard deck of playing cards, a deck may be used which has just red and black cards in it and in which all of the cards are marked with numerals. Two black cards may be marked with 15 yards, two with 20 yards and two with 25 yards, substituting thereby for the jack, queen and king of a standard deck. Otherwise the rules remain the same as indicated for a standard deck.

While the game has been described in connection with particular methods of play, it will be understood that different variations of these methods may be employed without departing from the scope of the invention. It will be understood, too, that the dials, or dice, or cards may be marked in various ways to suit a desired method of play.

While the invention has been described in connection with play of a game simulating the American game of football, it will be understood, also, that with suitable modifications, the game may be played to simulate "Rugby," or to simulate Soccer football. It will further be understood that with suitable modification in the game board and rules of play, my invention may be used for playing any game simulating a contest played on a graduated or ruled field, such as hockey, lacrosse, or polo.

In general, it may be said that while the invention has been described in connection with a particular embodiment thereof, it will be understood that it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinafter set forth and as fall within the scope of the invention or the limits of the appended claims.

Having thus described my invention what I claim is:

1. A game board for a football game having a field of play that is generally circular in shape

and which is graduated with a plurality of parallel spaces, each of which extends chordally across the circle, the number of said spaces being equal to one half the total number of spaces required for the field of play, the space at one end being designated the goal lines, and the other spaces being graduated away from said space with numbers of progressively increasing value, denoting yardage of the field, up to a number denoting half the full yardage of the field, said field being divided by a diametral line into two halves, one half of all the spaces lying at and constituting one half of the field of play and the other half of all the spaces lying at and constituting the other half of the field of play.

2. In combination, a football game board having a field of play that is generally circular in shape and which is graduated with a plurality of parallel spaces, each of which extends chordally across the circle, the space at one end being designated the goal lines, and the other spaces being graduated away from said space with numbers of progressively increasing value up to a number denoting half the full yardage of the field, said field being divided by a diametral line, which is perpendicular to the goal lines, into two halves, one half of all the spaces lying at and constituting one half of the field of play and the other half of all the spaces lying at and constituting the other half of the field of play, and a pair of pointers rotatably mounted centrally of said field and adapted to register with said graduations, one of said pointers being used to designate the position of play and the other pointer being used to designate the yardage to be gained.

3. In combination, a football game board which is graduated with a plurality of spaces to indicate yardage, the number of spaces constituting half the total required for a field of play and said spaces being divided transversely so that one half of all the spaces represent one half of the field of play and the other half of all the spaces represents the other half of the field of play, said spaces being graduated progressively from one end to the other up to a number denoting half the full yardage of the field and in the same direction for both halves of the field so that the two goal lines lie at the same end of the field, and a pair of pointers rotatably mounted centrally of said field and adapted to register with said graduations, one of said pointers being used to designate the position of play and the other pointer being used to designate the yardage to be gained.

FRANK R. GRAVES.
